[57] CLAIM

The ornamental design for a cabinet for storing pizza skins or the like, as shown and described.

DESCRIPTION

FIG. 1 is a perspective view, as seen from the upper right front, of a cabinet for storing pizza skins or the like, showing my new design;

FIG. 2 is a rear perspective view thereof;

FIG. 3 is a side elevational view thereof; and

FIG. 4 is a bottom plan view thereof.
